[57] CLAIM

The ornamental design for an oil filter crusher assembly, as shown.

DESCRIPTION

FIG. 1 is a front perspective view looking from above illustrating an oil filter assembly showing my new design;

FIG. 2 is a top plan view thereof further showing my new design;

FIG. 3 is a bottom plan view thereof;

FIG. 4 is a left elevational view thereof;

FIG. 5 is a right elevational view thereof; and,

FIG. 6 is a rear elevational view thereof.

*Fig. 2.**Fig. 1.**Fig. 3.*

*Fig. 4.**Fig. 5.**Fig. 6.*
